US00D675009S

(12) **United States Design Patent**
Votel et al.

(10) **Patent No.:** **US D675,009 S**
(45) **Date of Patent:** **** Jan. 29, 2013**

(54) **RETRACTABLE LANYARD**

(75) Inventors: **Thomas Votel**, Sunfish Lake, MN (US);
Justin Kostner, Minneapolis, MN (US);
Jeffrey A. Popowski, Roseville, MN
(US)

(73) Assignee: **Tenacious Holdings, Inc.**, St. Paul, MN
(US)

(**) Term: **14 Years**

(21) Appl. No.: **29/408,429**

(22) Filed: **Dec. 13, 2011**

(51) LOC (9) Cl. **03-01**

(52) U.S. Cl. **D3/215**

(57) **CLAIM**

We claim the ornamental design for a retractable lanyard, as shown and described.

DESCRIPTION

FIG. 1 is a perspective of our retractable lanyard.

FIG. 2 is a front view thereof.

FIG. 3 is a rear view thereof.

FIG. 4 is a side view thereof.

FIG. 5 is a top view thereof; and,

FIG. 6 is a bottom view thereof.

The broken lines appearing in the figures are not intended to form part of the claimed design and are provided for illustrative purposes only.

1 Claim, 4 Drawing Sheets
